Term of patent 14 years

Int. Cl. D7—04

U.S. Cl. D44—29

FIG. 1.

FIG. 2.

FIG. 3.

FIG. 4.

FIG. 1 is a side elevational view of a combined washer and scaler for fish embodying my design;

FIG. 2 is a top elevational view of same;

FIG. 3 is a bottom elevational view of same; and

FIG. 4 is an end elevational view of same.

A side elevational view taken from the side opposite that shown in FIG. 1 is essentially a mirror image thereof.

I claim:

The ornamental design for a combined washer and scaler for fish, as shown and described.
